5 Claims. (Cl. 333—24.1)

This invention relates to microwave phase shifters incorporating ferrite material so that the phase shift is controllable electrically.

Electrically controllable phase shifters have useful properties at microwave frequency as they may be used in various configurations to obtain a number of useful devices. Ferrite phase shifters may be classed as reciprocal (in which case the phase shift is the same whichever way the power is flowing) or non-reciprocal (in which case the phase shift changes sign with direction of power flow). Non-reciprocal phase shifters are particularly considered here as they may be used in the construction of circulators. These are devices in which power enters and leaves ports in a certain order, e.g. power enters one arm and leaves by a second arm, enters by the second arm and leaves by a third arm and so on.

In the case of a switchable circulator the order may be reversed on demand by some external signal which changes, for instance, the direction of a magnetic field.

With conventional phase shifters used in such switchable circulators it is difficult to obtain rapid phase shift owing to the system geometry which requires that high energy be stored in the magnetic field. In addition to this problem the rapidly changing magnetic field causes adverse eddy currents which tend to slow down the change. To overcome this difficulty, attempts have been made to use closed tubes of ferrite material but considerable difficulty was experienced in the manufacture of these tubes which were also required to have a rectangular shape of high aspect ratio.

One object of the present invention is to overcome these difficulties by the use of commercially available circular ferrite rings and to match such circular rings to the waveguide impedance.

Another object is to ensure that low aspect ratio (circular rings) may be made to give large phase shift with low loss.

In the present invention, a pulsable phase shifter has circular ferrite rings mounted on a dielectric rod with their axes coincident with the axis of a rectangular waveguide (the dielectric rod on which the rings are mounted also has its axis coincident with that of the guide), and optimization of the phase shift is obtained by narrowing the walls of the waveguide and matching of the wave into and out of the structure is obtained by suitable adjustment of the spacings between the rings.

Further features of the invention and the constructional details thereof will be clear from the following description referring to the accompanying drawings in which FIG. 1 shows a perspective view of one embodiment of the invention with part of the waveguide structure partly broken away to show the interior. FIGS. 2 and 3 are a longitudinal sectional view and end elevation respectively of a modified structure giving progressive variations of phase shift, while FIG. 4 is a block diagram of a suitable control system for the structure of FIGS. 2 and 3. For clarity, the conductors are not shown in FIG. 3.

The pulsed microwave phase shifter illustrated in FIG. 1 consists of a hollow rectangular waveguide 1 within which are grouped circular ferrite rings 2 threaded on a cylindrical dielectric rod 3, the axes of the rings 2 and the rod 3 coinciding with the longitudinal axis of the wave-

2

guide. In the region of the groups of ferrite rings, the longer transverse internal dimension of the waveguide is reduced or constricted by inwardly projecting portions 4 of the waveguide walls to increase the amounts of phase shift resulting from changes in the magnetic states of the ferrite rings, and this constriction of the wider transverse dimension of the waveguide also has the incidental advantage of minimizing the number of, and coupling to, unwanted modes of propagation of R.F. energy along the waveguide.

Pulses of current for altering the magnetization of the ferrite rings are applied through leads 5 and a metal strip 6 along the middle of the rod 3. The dielectric rod 3 is mounted on and supported by the conducting strip 6 which is in turn supported at its ends by the rigid leads 5 passing through insulated sleeves 7 in sockets 8 on the outside of the waveguide. The ends of the rod 3 can be stepped as shown at 9 for impedance matching.

In the modified structure illustrated in FIGS. 2 and 3 there is shown another important aspect of the invention, namely the subdivision of groups of the ferrite rings so that more than two different phase shifts are possible through the device, each subdivision having its own current linking path. In this way some groups of the rings 30 can be switched magnetically so as to oppose others instead of all the rings being switched together into the same magnetic states, which is the case in the FIG. 1 construction. In the arrangement now to be described, one, two, four, eight or sixteen rings may be switched independently 35 by means of the thin metal conductors which link these numbers of rings. This particular arrangement can therefore be designated a digital phase shifter since it accepts a digitally coded input. In FIGS. 2 and 3 is shown an embodiment of a five bit binary coded digital phase shifter 35 for obtaining up to $\pm 180^\circ$ phase shifts, to an accuracy of $\pm 5\%$, and it is particularly suitable for the control of the direction of an aerial beam.

In the digital phase shifter which is illustrated in FIGS. 2 and 3, the structure is built up from metal and insulated parts held together by screws 10 and consists of metal end portions 11 of hollow rectangular waveguide of normal internal dimensions and incorporating end flanges 12 for coupling to other structures, and a metal middle portion 13 of the same internal width as the end portions 11 but constricted in its wider cross-sectional internal dimension to nearly one-half of the corresponding dimension of the end portions 11. The metal waveguide walls have clearance slots 14 through which pass the external leads 5 for the conduction of pulsing currents, the leads 5 being secured in place by strips 15 of rubber or other electrical insulation clamped between the metal halves of the waveguide. The cylindrical dielectric rod 3 is supported from the larger end leads 5 and has threaded on it the circular ferrite rings 2 which are spaced as shown so that groups of one, two, four, eight or sixteen 55 are linked by individual conductor strips 6 within the dielectric rod, the ends of said strips being attached to the external leads 5 as shown. The locations of the end ferrite rings on the rod to match into the waveguide impedance and to set the amounts of phase shift achieved by magnetization of the rings are predetermined by an experimental set-up (not shown) in which R.F. power is fed into a waveguide of the same internal dimensions as the constricted portions illustrated and containing circular ferrite rings adjustable in position along a dielectric rod, with tapering lossy material beyond the adjustable rings to absorb the incoming R.F. power, and the positions of the rings are adjusted for a best impedance match in the usual way with the desired phase shifts, and the ring locations so determined are used in the final structure.

In the construction shown in FIGS. 2 and 3 a current pulse to the lead and strip through one ferrite ring can produce $\pm 5\%$ phase shift, which is a function of its dimensions, in particular the length of the ring along the axis of the waveguide, and the axial length of the ring. These dimensions can be adjusted experimentally to give the correct phase shift. A pulse to the lead and strip linking two ferrite rings can produce $\pm 1\frac{1}{4}$ ° phase shift, or through four, eight or sixteen give phase shifts of $\pm 22\frac{1}{2}$ °, ± 45 °, or ± 90 ° respectively or in any combination of these amounts.

An example of a control system for a digital phase shifter as just described is illustrated in FIG. 4. An input signal of serially fed phase-angle information from a computer is fed into a shift register and thence to a modulator and store which also receives an executive command input and a command reversal input, the five bit output therefrom being parallel fed control pulses to the phase shifter as in FIGS. 2 and 3 but represented by the row of five blocks along the top of FIG. 4 to indicate the different amounts of phase shift obtainable in the microwave power entering and leaving the phase shifter.

Both the phase shifter constructions described can contain air or inert gas or can be filled with a low-loss liquid dielectric such as liquid paraffin contained between windows across the waveguide at the ends of the region occupied by the ferrite ring assembly.

If greater accuracy than that of a five bit digital phase shifter is required it would usually be necessary to further subdivide the device and have for instance a seven bit phase shifter. An alternative, however, which may sometimes assist the designer to obtain greater accuracy, is to use the demagnetized state of each subdivision. A demagnetized state would prevail in a subdivision immediately after a demagnetizing pulse, after such a pulse this subdivision would have no differential phase shift.

A "demagnetising pulse" would differ from pulses which magnetize the rings in either one or other of two directions in that after such a "pulse" the ring is demagnetized. Such a "pulse" could consist of a train of pulses of alternate sign and gradual decreasing amplitude. This type of "pulse" is readily obtainable from well known circuits.

By the ability to apply demagnetizing pulses to any subdivisions it would be possible to make a digital phase shifter in ternary code. In such a device the number of rings in each subdivision would vary in the ratio of three to one instead of the previously described two to one. The resultant advantages of the fewer subdivisions would be offset by the greater complexity in the computing of the correct types of pulse required for a given phase shift. The embodiment of such a device would be similar to that shown in FIG. 2 except for the different ratio between numbers of rings in the subdivisions.

An alternative to the use of a full ternary coded device would be the use of a demagnetizing pulse only on the smallest subdivision. In this case an extra factor of two in accuracy is obtained without any extra subdivision of the device, in addition the complication of utilizing the ternary code is avoided.

Phase shifters in accordance with the invention have the following advantages:

(a) The circular ring geometry has an advantage over others as it is the one that has the lowest flux leakage and hence the energy of switching is minimized. In addition, as the device is of a field displacement type, it is of advantage to have the ferrite toroid enclosing the maximum area. The circular geometry achieves this too. Previous devices have used 1.7 times the amount of ferrite required by the present device. Hence for a given ferrite the switching energy will be this factor lower. For the same reason the losses for a given quality of ferrite will be lower.

(b) The use of separate rings of ferrite enables their spacing to be adjusted to obtain a good match over a

very wide bandwidth. The use of circular rings as opposed to the high aspect ratio rectangular blocks is made feasible by the narrowing of the spacing between the walls of the waveguide in the region of the ferrite rings. This has three beneficial effects: (1) To increase the amount of phase shift for a given amount of ferrite material; (2) to flatten the curve of phase shift vs. frequency so that the device may be used over a wide bandwidth; (3) to minimize the number of modes in the dielectric-ferrite-waveguide ensemble, thus lossy resonances may be eliminated over a wide bandwidth.

Another advantage of the use of circular rings is that commercially available rings of ferrite made for quite a different purpose may sometimes be used, thus reducing the cost of production of the devices.

(c) A digital phase shifter may be more easily constructed using separable rings and an arrangement such as FIG. 2 represents a typical embodiment. The separation of the rings, in any case required for obtaining a match, assists in the routing of the current carrying conductors required to switch the various groups of rings.

I claim:

1. A microwave phase shifter for pulsed operation comprising a hollow waveguide of rectangular cross-section having within it a cylindrical dielectric rod disposed with its longitudinal axis coincident with the longitudinal axis of the waveguide, an assemblage of circular rings of ferrite threaded on said rod and mounted thereon in predetermined locations along it, a metal strip along said rod and external leads connected to the strip for the conduction of pulsing current through said strip, and constriction of the wider internal cross dimension of the waveguide, which constriction extends along the region occupied by the ferrite ring assemblage to enhance the effective phase shift resulting from magnetization of the ferrite rings by the pulsing current.

2. A microwave phase shifter as claimed in claim 1 wherein the ferrite ring assemblage comprises individual groups of rings with a separate pulse conducting strip linking each group.

3. A microwave phase shifter as claimed in claim 1 and having the ferrite ring assemblage formed by separated sets of rings arranged as a binary power sequence of numbers of rings per set with a separate pulse conducting strip linking each set.

4. A microwave phase shifter as claimed in claim 1 and filled with a liquid dielectric contained between windows across the guide at the ends of the region occupied by the ferrite ring assembly.

5. A microwave phase shifter as claimed in claim 1 and built up from metal end portions of hollow rectangular waveguide in two longitudinal halves and having end flanges for coupling to other structures and a metal middle portion, also in two halves, of waveguide constricted in its wider cross-sectional internal dimension, said portions being secured together and having clearance slots around the pulse conduction leads which are held in place and insulated from the metal parts by rubber strips clamped between the half portions of waveguide.
